UNITED STATES PATENT OFFICE.

JOHN C. DEVITT, OF ELYRIA, OHIO.

PIPE-BENDER.

1,056,781.

Specification of Letters Patent.

Patented Mar. 25, 1913.

Application filed July 19, 1909, Serial No. 508,972. Renewed August 14, 1912. Serial No. 715,132.

To all whom it may concern:

Be it known that I, JOHN C. DEVITT, a citizen of the United States, and resident of Elyria, in the county of Lorain and State of Ohio, have invented certain new and useful Improvements in Pipe-Benders, of which I hereby declare the following to be a full, clear, and exact description, such as will enable others skilled in the art to which 10 it appertains to make and use the same.

The objects of the invention are to provide a device for bending an elbow in a metal pipe without distorting the walls or affecting the inside diameter in any direction.

Further objects are to provide an adjustable device whereby a number of sizes of pipes can be bent and the arc of the circle of the bend can also be varied.

Further objects are to combine with the bending devices a suitable holding device or holding jaws adapted to retain one end of the pipe while the other is being forcibly bent into shape, and also to provide a reaming tool adapted to give a flaring end to the pipe while exposed in the vise, so that the bent tube can be employed as a conduit for electric wires, and the wires will enter freely without danger of injury to their insulation or protecting outer coating.

The invention further comprises the combination and arrangement of parts and construction of details as hereinafter described, shown in the accompanying drawings and 35 specifically pointed out in the claims.

In the accompanying drawings, Figure 1 is a plan view of the device showing a pipe in position while being bent; Fig. 2 is a side elevation thereof, showing the bending 40 formers or dies; Fig. 3 is an end elevation, showing the larger or forming die, dovetailed into the standard, so that it can readily be removed for the substitution of one of a different size; Fig. 4 is a perspective view of the larger fixed die or former.

In these views, 1 is a bed plate adapted to support the movable parts, 2, 2 are vise jaws adapted to grip and secure one end of a pipe P while it is being shaped by the 50 dies, 3 is a fixed former or die, block upon the outer edge of which is recessed the groove 4, which is shaped to the arc of the circle in which the pipe is to be bent. This fixed die is removably secured to the bed 55 plate by means of the dovetail flanges 5, 5 adapted to be inserted in grooves 6, 6 in the

bed plate. A pin 7 is adapted to pass through the openings 8, 8' in both bed plate and die. Other spaced openings 9 and 10 in the bed plate permit of the insertion 60 of the pin at varying distances from the center line of the jaws, so that other dies of greater size can be inserted when the larger pipes are to be bent or are to be bent in a larger arc of a circle. In this manner 65 the several dies will produce curves of varying radius according to the shape of the grooves.

The device by means of which the pipe is forced over the forming die to give it the 70 necessary curvature comprises the roller 11 pivoted on a pin 12 in the hole 15 within the fork 13, which is pivoted at and swings from the pin 7 which is located at the central point from which the arc of the fixed 75 die is struck. In this manner when the fork is swung by its handle 14 the roller 11 will revolve about the fixed die and force the pipe thereon to give it the required shape.

The pivotal pin 7 can be placed within 80 any of the openings 8, 9 and 10 which are the central points of all the circular grooves of various sizes and the roller 11 can be pivoted in any one of the holes 15, 16 or 17 to accommodate its position to the relative size 85 of any one of the fixed dies.

At 20 is shown a pointed or tapered reamer pivoted in a lever 21 and rotatable therein by means of the crank 22, so as to counter sink or flare the inner edge of the 90 pipe at 23. To give variability to the position of the reamer to accommodate it to the size of the pipe, so that it can be centered therein, the lever 21 is loosely connected with the bed plate by means of the spring 95 24 by means of which also elastic pressure upon the reamer can be obtained.

Having described the invention what I claim as new and desire to secure by Letters Patent is:—

1. In a pipe bending device, the combination with a bed plate, of a vise thereon, a removable die block therein, having a curved groove in its outer edge corresponding to the desired arc of the pipe elbow, a central 105 opening in said block within said arc, a pin therethrough, and a fork pivoted upon said pin, a roller pivoted in said fork, adapted to engage the outer side of said pipe, a pivot pin for said roller, said fork provided with spaced openings in which said roller pivot is alternately insertible, said

bed plate provided with corresponding pivotal openings for the pivot pin of said fork.

2. In combination, in a pipe bending device, a bed plate, a vise thereon adapted to hold said pipe while it is being bent, a die block provided with a groove on its outer edge curved in an arc of a circle, said block provided with dovetail flanges on its inner edge and said bed plate provided with corresponding dovetail recesses, a forked lever and a pivot pin therefor in said fixed die block, centrally located in said arc, and a roller pivoted in said fork, said roller adapted to revolve about said fixed die block when said lever is swung about said pin therein.

3. In a pipe elbow making device a bed plate detachable die blocks adapted to be alternately secured thereon, said die blocks

having grooves on their outer faces, curved 20 to the desired arc of the elbow, each die block provided with an opening centrally located in said arc, and said bed plate provided with spaced openings corresponding in position to the said openings in said die blocks when placed in their several positions, a pivot pin adapted to be inserted in said openings in said die blocks and bed plate, a lever pivoted on said pin, a roller pivoted in said lever, and a vise in said bed plate 30 adapted to hold pipe while said elbow is being made therein.

In testimony whereof, I hereunto set my hand this 10th day of June 1909.

JOHN C. DEVITT.
